16 Claims. (Cl. 178—71)

Our invention relates to a telegraphic repeater system, and more particularly to a repeater system for wire telegraphy employing impulses of different polarity and telephone repeaters having amplifier characteristics.

In wire telegraphy employing impulses of different polarity effects of disturbing currents are more noticeable than in ordinary telegraphy. Special attention must, in particular, be paid to the high voltages liable to injure attendants or operators. It would, in itself, be possible to render the telegraph apparatus high-tension-proof, as has been done in sectionalized telephony, for instance. This is, however, unsuitable for telegraphy, as it would then be necessary to abandon the customary construction of the racks, in which the individual parts and relays are so arranged as to be readily accessible. Grounding provisions at the lines would indeed also be as safeguard against dangerous voltages, but these, due to the necessary ground-symmetrical arrangement, again cause difficulties in the phantom utilization of telephony. In telephonic communication it is known to subdivide the line into sections and to block or protect the apparatus at the ends of the line against induced voltages by repeaters.

Such an expedient can be utilized in impulse telegraphy by sending direct current impulses when closing the key in the telegraph transmitter. By the protecting repeater or more properly transformer at the sending side the direct current impulses are converted into pure impulses and sent over the line; at the receiving side the impulses may through the protecting transformer located here be passed to a relay adjusted for impulse reception. Wire telegraphy of the polar-duplex or briefly called impulse type has, however, a number of drawbacks, the most prominent of which is that a comparatively small energy is sent over the lines, which consequently are more liable to be adversely affected by the switching operations in neighboring high tension power lines. The impulse peaks of impulse telegraphy, furthermore, more easily cause flutter phenomena, more particularly in loading coils and the like, than the currents of the direct current telegraphy operating with smaller amplitudes.

According to our invention these drawbacks are eliminated and yet a protection of the telegraph apparatus against high tension influences is obtained by the sending and/or receiving apparatus of the telegraph system being guarded by the transformers against disturbing voltages on

the line, and by providing apparatus for sending the telegraph signals over the line in the form of direct current impulses. This may, for instance, be effected by operating with direct current in front of the protective transformer (that is, on the input side) and connecting behind the transformer, which resolves each direct current impulse into impulses of opposite direction or polarity, a relay, for instance, with a holding current winding whose local circuit sends direct current impulses over the line. Such a system has, however, still the disadvantage that the relay and the feeding battery, which directly generate the line currents, are still located on the side of the transformer affected by the disturbing voltage, and therefore, in order to prevent accidents, must not be accessible under normal conditions.

According to a further feature of our invention, the telegraph currents are keyed as alternating currents and sent over the protective transformer. Beyond the protective transformer the alternating current impulses are converted by rectifiers into direct current impulses, which are then sent over the line. On the receiving side the direct current impulses reach the protective transformer on the input or receiving side and are there resolved into impulses which operate the receiving relay, if desired after amplification.

In the drawing affixed hereto—

Fig. 1 illustrates the principle of the invention with reference to a telegraph apparatus operating on the polar-duplex wire system and impulse reception; Fig. 2 is a partial diagram of another embodiment, and Fig. 3 is a diagram of a third embodiment.

Referring to Fig. 1, alternating current is according to the invention sent, by closing the key S, to the protecting transformer or stopper transformer U₁ for which alternating current is supplied to the rectifier system g. The rectifier system effects a complete rectification. In this system direct current impulses are generated which pass through the filter F₁ to the line l. Hence they are passed through a filter F₂ to the stopper transformer U₂, which converts them into impulses (two of opposite direction for one signal), which reach the impulse relay R. At t we have indicated the telephone connections or cables. In the repeater system according to Fig. 1 each disturbing impulse is, due to the construction of the transformer, resolved into two impulses of opposite direction which follow each other directly.

Contrary to Fig. 2 each disturbing impulse is,

however, due to the design of the transformer U_2 , resolved into two impulses of opposite direction, which follow each other directly, as distinguished from the telegraph currents, whose 5 impulses of opposite direction are separated by the duration of a signal. The effect of disturbing impulses may thus be reduced to the minimum length of the signal by adjusting the time constant of the relay R .

10 In the system illustrated in Fig. 1 an impulse amplifier may naturally be connected up ahead of the receiving relay R .

Such a wrong operation of the receiving relays may, however, to a greater extent be avoided by 15 leading the direct current impulses arriving from the line to an apparatus which converts them into alternating current impulses, which reach the receiving apparatus through the stopper transformer.

20 According to our invention this is preferably effected by leading the direct current impulses into a magnetic amplifier consisting of a choke or a rejector circuit, which is fed from a source of alternating current of higher frequency than the impulse frequency. Magnetic amplifiers have in comparison with valve amplifiers the great advantage that they reproduce the low frequencies very well, and are thus particularly useful for the amplification of the impulse telegraphy signals. They are, furthermore, not so sensitive to the replacement of circuit elements 25 as valve amplifiers. Valve amplifiers cannot be used simultaneously in both traffic directions, as the amplifiers of the transmission direction block 30 the amplifiers of the opposite direction.

According to our invention a magnetic amplifier is employed as a transmitting and as a receiving amplifier respectively or as an intermediate amplifier, the windings of which are so 40 designed and so connected to the duplex line serving for the transmission of the signals in the lines leading to the transmitting and receiving apparatus, that together with a balancing network of the transmission line it functions as a 45 balancing repeater between the three lines. In this way a two-wire or forked repeater for telegraphy may be built up which corresponds with the two-wire intermediate repeaters and forked repeaters in telephone systems. By the application 50 of the iron repeaters the above-mentioned drawbacks of the valve amplifiers are eliminated. The repeater or transformer according to the invention is furthermore at the same time available for both directions of traffic. Transmitting 55 and receiving circuits may be completely uncoupled provided the artificial balancing line is sufficiently accurate. The magnetic amplifiers consist in their simplest design of an iron-containing choke coil, which is connected in an 60 alternating current circuit whose frequency is higher than the highest frequency to be amplified. The iron choke coil is so magnetically biased by direct current, that it varies its alternating current resistance when the low frequency 65 voltages to be amplified are applied with the frequency of these voltages. This causes a modulation of the alternating current of the higher frequencies. After the rectification of the 70 modulated carrier frequency the amplified low frequency is obtained.

By the introduction of the rectifiers, which are necessary when making use of magnetic amplifiers, a new phenomenon appears as compared with the normal balancing connections, 75 such as are used in telephone systems, for in-

stance. The rectifiers of the magnetic forked amplifiers are firstly traversed by the amplified current (outgoing current) of the respective amplifier, and secondly by the current arriving from the opposite side (incoming current). The 5 impedance of the rectifier is not constant for the incoming current and varies with the load of the rectifier, i. e. with the cadence of the outgoing current. This phenomenon causes the incoming current to be modulated by the outgoing current. 10

According to a further feature of our invention this modulation effect is reduced by the outgoing current not being reduced to zero and preferably being at all times maintained larger than $\frac{1}{3}$ of its maximum value. The modulation 15 effect is not entirely prevented in this way, it is true, but confined within limits which according to experience generally do not cause any disturbances of the telegraph service. The desired control of the modulation effect may, for in- 20 stance, be attained in the transmitter by a bridging resistance for the transmitter key, and in the telephone repeater by the choice of a corresponding bias magnetization. If the modulation still continues to cause disturbances in spite of these 25 expedients, an attenuation member, preferably adjustable, may according to a further feature of our invention be connected behind the rectifier, the resistance of which is so proportioned that the variation of the impedance of the rectifier no 30 longer plays an important part. The attenuation member may at the same time be designed as a correcting device for controlling the frequencies of the telephone repeater.

The incoming current taken up by the rectifier 35 represents an additional load on the transmission line. If for any reason it is desirable to reduce this load, our invention provides for the compensation of this direct current by an additional source of direct current.

As distinguished from the telephone repeaters the risk of self-excitation in the telegraph repeater can be reduced by the choice of a repeater or transformer characteristic which is not linear in a definite way. Such a non-linearity of the 40 characteristic exists in an ideal way in every contact relay. In this relay the amplification is zero up to reaching the limit of response and then rises to a very high value at the moment of reversal. In a repeater or transformer with such 45 a non-linear characteristic a resonant rise of oscillations for self-excitation is impossible, because the current due to faulty balancing returned into the input circuit of the repeater is located below the threshold of response. In 50 magnetic telephone repeaters a similar characteristic may be obtained by a suitable biasing of the rectifier with a direct current voltage, for instance, and thus the tendency to recoupling be reduced. This result may also be attained by 55 a shunt consisting of a one-way rectifier located behind the rectifier, the one-way rectifier being biased in such a way that it operates in the lower bend of its current voltage characteristic. A similar effect may also be attained by choosing 60 the magnetic conditions of the telephone repeater in such a way that in case of low modulation the amplification is small, and large in 65 case of medium or high modulation. This is, for instance, possible by a corresponding choice of 70 the saturation of the iron of the telephone repeater.

Fig. 2 of the drawing illustrates a system or arrangement according to our invention applied to polar-duplex wire telegraphy, where the tele- 75

graph circuits are superposed on telephone circuits. As regards the transmitter the system is identical with Fig. 1. At the receiving side the direct current impulses pass, however, through filters F_2 to the rejector circuit designed as a repeater, which is equipped with two sets or groups of choke coils or windings D_1 , D_2 , protected against high voltage discharges or leaks from the line. In this way the entire receiving apparatus with the exception of the filter F_2 may be located on the protected side of the repeater. The alternating current feeding the rejector circuit D_2 is through a protective repeater or transformer U_3 supplied to a rectifier G in the output of which there are developed alternating currents which according to the design of the rectifier, are of the frequency of the fundamental oscillation of the source of alternating current or of higher harmonics, in addition to a direct current component which serves for the magnetic biasing of the chokes D_1 , D_2 . The filter F_3 interposed between the rectifier G and the choke D_2 is adapted to permit direct current and one of the alternating current frequencies to pass. By way of a rectifier g_2 , the rejector circuit is connected with the impulse relay R .

The transformers serving for protective purposes are preferably designed to be high-tension-proof and with grounded shields to the transformer windings, as in the example described above.

Fig. 3 illustrates a forked transformer A installed in a telegraph station, and destined for the amplification of the incoming currents, and an intermediate repeater B , which amplifies the telegraph signals arriving from the forked repeater A and passes them on to an arrangement similar to A , not shown in the drawing.

In Fig. 3 of the drawing SG indicates an alternating current generator whose current is dispatched by closing the transmitting key ST . When the key is depressed to close the circuit, this alternating current is supplied to the rectifier arrangement G_1 through the transformer U_1 .

Between the transmitting or sending equipment described and the receiving apparatus designated ER is connected the magnetic repeater MV , which handles the transmission of the signals sent to the outgoing line L_1 and the transmission of the signals arriving over this line to the receiving apparatus ER . This magnetic repeater includes the iron-containing inductances W_1 to W_6 . A magnetic amplifier consists generally of biased iron choke coils connected in the circuit of a source of high frequency. The iron chokes W_1 and W_2 are biased through the windings W_5 , W_6 , which are traversed by the direct current of the battery B' . The high frequency supplied by the generator H is fed to the chokes W_1 and W_2 through the transformer U_3 . The signals arriving over the line L_1 and to be amplified traverse the choke coils W_1 and W_2 in the same direction and thereby vary the alternating current resistance of the iron chokes for the high-frequency carrier oscillation. The carrier frequency is thus modulated by the currents to be amplified. The modulated oscillations are through the windings W_3 and W_4 and the transformer U_2 passed to the receiving apparatus ER after rectification by means of the rectifier equipment G_2 . The transformation ratio of the transformer U_2 is made variable to enable regulation of the repeater. It will be understood, however, that other means for controlling the

degree of amplification may be used, for instance the variation of the amplitude of the carrier frequency. The line L_1 is bridged for the carrier frequency by means of the condenser C_2 .

To enable the magnetic amplifier MV to carry out its function as a balancing repeater, the choke coils W_1 and W_2 are each provided with a midpoint tap S_1 and S_2 . To these taps are connected the lines leading to the transmitting apparatus. Under the assumption that the artificial balancing line N is a close simulation of the resistance connected to the terminal points A_1 and A_2 of the windings W_1 and W_2 , and more particularly of the resistance of the transmission line L_1 , the currents emanating from the transmitting apparatus traverse the two halves of the windings W_1 and W_2 in opposite directions and in equal strength. This prevents a transmission of the sending currents to the windings W_3 and W_4 and thus to the receiving apparatus. Due to the design of its windings according to our invention the magnetic amplifier MV thus takes over the functions of a balancing repeater between the line L_1 and the transmitting and the receiving apparatus. The transmitting and the receiving apparatus are uncoupled from each other.

As already pointed out it is necessary to prevent the direct current arriving over the line L_1 and traversing the rectifier G_1 (the incoming current), from being modulated by the outgoing current of said rectifier. For this purpose the transmitter key ST is according to our invention bridged by the adjustable bridging resistance UW . As a further means for eliminating the said modulation there is connected in circuit behind the rectifier G_1 , a variable attenuation member D in the form of a bridged T-connection. The attenuation member may at the same time be used as a frequency correcting device.

The intermediate repeater contains the repeaters MV_1 and MV_2 destined for the two different directions of traffic. The repeater MV_1 amplifies in the direction $A-B$ and the repeater MV_2 in the opposite direction. The two magnetic repeaters are of a construction similar to that of the repeater described at A , so that a detailed description appears superfluous. They act at the same time as balancing repeaters so that the signals amplified by MV_1 , for instance, which are supplied to the amplifier MV_2 at its points of symmetry S_2 , are only returned into the line L_2 and not amplified by the repeater MV_2 to the magnetic repeater MV_1 .

At D_3 and D_4 adjustable attenuation members are indicated, which are intended to partly neutralize the effect of the variable output impedance of the rectifiers G_1 and G_2 , and at the same time serve to control the frequencies of the repeater circuit. The direct current generators G_1 and G_2 supply direct current which serves for the compensation of the direct current taken by the rectifiers G_1 and G_2 . Similarly, a direct current generator G_3 is associated with the variable attenuation member D .

For the sake of completeness there is in this diagram of connections also provided a two-wire intermediate repeater SV for the amplification of the superposed speech currents, which is connected to the two lines L_1 and L_2 through the repeaters or transformers SU_1 and SU_2 respectively. The condensers KL_1 and KL_2 and the coil lines SL_1 , SL_2 serve in a well known manner for the separation of the telegraph and telephone currents.

To explain the mode of operation of the intermediate repeater circuits the transmission of telegraph signals in the direction A—B will now be concisely described. The telegraph signals arriving over the line L_1 pass over the coil line SL_1 into the magnetic repeater MV_1 , in which takes place a modulation of the carrier oscillations supplied by the source of high frequency current H_1 . The modulated oscillations are through the transformer U_1 supplied to the rectifier GL_1 , in whose output circuit there exist the telegraph currents arriving over L_1 with amplified amplitude, and which are passed through the attenuation apparatus D_3 to the symmetry points S_2 of the repeater MV_2 . Assuming a close simulation of the line L_2 by the artificial balancing line N_2 the amplified currents pass from the symmetry points S_2 through the coil line SL_2 into the line L_2 without generating amplified currents in the output of the magnetic repeater MV_2 .

It will be readily understood that as a matter of course modifications in the connections described may be made without departing from the ambit of our appended claims. Thus the windings W_2 , W_4 and W_6 of the magnetic repeater shown at A may, for instance, be omitted. In the same way it would be possible to replace the attenuation circuit D by a simpler connection.

We claim as our invention:

1. Telegraphic repeater system, more particularly a wire telegraph system, including telegraph apparatus, transformers so connected as to protect the telegraph apparatus against disturbing voltages on the line, said transformers being located at the sending and at the receiving ends of the line, an alternating current circuit at the sending end of the line, a key for opening and closing said circuit, rectifier apparatus interposed between the sending transformer and the line, whereby the alternating current signals produced by operating said key will be converted into direct current signals, which are sent over the line, a receiving circuit located beyond the transformer at the receiving end of the line, and a device located between said transformer and the line, for converting the direct current signals into alternating current signals, which pass through the said transformer into the receiving circuit.

2. Telegraphic repeater system, more particularly a wire telegraph system, including telegraph apparatus, transformers so connected as to protect the telegraph apparatus against disturbing voltages on the line, an alternating current circuit, means for opening and closing said circuit, rectifier apparatus interposed between the transformer at the sending station and the line to convert the alternating current impulses produced by the operation of said means into direct current signals, a magnetic amplifier including choke coils connected with the line, a source of alternating current connected with said coils, a transformer connected with said amplifier, a receiving relay, and rectifying apparatus interposed between said transformer and said relay.

3. In a repeater system for wire telegraphy of the polar-duplex type, including telegraph apparatus, transformers so connected as to protect the telegraph apparatus against disturbing voltages on the line, a magnetic amplifier adapted to amplify the telegraph signals, a double line constituting a transmission channel common to both directions of traffic, two transmis-

sion channels each constituting a one-way line, and an artificial balancing line connected with said double line, said amplifier having coils so designed and connected with said lines that it will act as a balancing repeater between the three transmission channels.

4. In a repeater system for wire telegraphy of the polar-duplex type, including telegraph apparatus, transformers so connected as to protect the telegraph apparatus against disturbing voltages on the line, an alternating current circuit, means for opening and closing said circuit, a rectifier for converting alternating current impulses produced in said circuit, into direct current impulse telegraph signals, a magnetic amplifier adapted to amplify the telegraph signals, and an adjustable attenuation member connected in parallel with said rectifier.

5. In a repeater system for wire telegraphy of the polar-duplex type, including telegraph apparatus, transformers so connected as to protect the telegraph apparatus against disturbing voltages on the line, a magnetic amplifier adapted to amplify the telegraph signals, and a biased one-way rectifier connected in shunt to said amplifier.

6. In a telegraph system, more particularly a system of composite telegraphy and telephony, a metallic line circuit adapted to transmit direct current impulses, a transmitting circuit comprising a source of alternating current and means for transmitting telegraph signals from said source of current, a transformer inductively connecting said transmitting circuit with said line circuit and adapted to protect said transmitting circuit from disturbing voltages on said line circuit, and rectifying means interposed between said transformer and said line circuit for converting alternating current telegraph signals transmitted from said transmitting circuit into direct current signals which are to be sent over the line.

7. In a duplex telegraph system, more particularly a system of composite duplex telegraphy and telephony, a metallic line circuit adapted to transmit direct current impulses in both directions, a transmitting circuit comprising means for transmitting direct current telegraph signals into said line circuit, a receiving circuit for receiving direct current telegraph signals from said line circuit, an artificial line balancing out said line circuit, and a magnetic amplifier between said line circuit and said receiving circuit for amplifying incoming direct current telegraph signals, said magnetic amplifier comprising a plurality of coils in inductive relation to each other and in connection with said artificial line operating as a hybrid coil for coupling said transmitting circuit with said line circuit and uncoupling it from said receiving circuit.

8. In a duplex telegraph system, more particularly a system of composite duplex telegraphy and telephony, a metallic line circuit adapted to transmit direct current impulses in both directions, a transmitting circuit comprising means for transmitting direct current telegraph signals into said line circuit, a receiving circuit for receiving direct current telegraph signals from said line circuit, a magnetic amplifier interconnected between said three circuits, comprising a plurality of coils operating as a hybrid coil arrangement for uncoupling the receiving circuit from the transmitting circuit, and a source of direct current for magnetically biasing the coils of said magnetic amplifier to such a degree that the amplitude of the output current of said am-

plifier, in the absence of telegraph signals, will not fall down to zero.

9. In a duplex telegraph system, more particularly a system of composite duplex telegraphy and telephony, a metallic line circuit adapted to transmit direct current impulses in both directions, a transmitting circuit comprising means for transmitting direct current telegraph signals into said line circuit, a receiving circuit for receiving direct current telegraph signals from said line circuit, a magnetic amplifier interconnected between said three circuits, comprising a plurality of coils operating as a hybrid coil arrangement for uncoupling the receiving circuit from the transmitting circuit, and a source of direct current for magnetically biasing the coils of said magnetic amplifier to such a degree that the amplitude of the output current of said amplifier, in the absence of telegraph signals, will be higher than zero but not higher than about one third of the maximum amplitude.

10. In a duplex telegraph system, more particularly a system of composite duplex telegraphy and telephony, a metallic line circuit adapted to transmit direct current impulses in both directions, a transmitting circuit comprising a source of alternating current and a sending key for producing alternating current telegraph signals from said source of current, rectifying means adapted to convert said alternating current signals into direct current signals and to send them into said line circuit, a receiving circuit for receiving direct current telegraph signals from said line circuit, a magnetic amplifier between said line circuit and said receiving circuit comprising a plurality of coils arranged as a hybrid transformer for uncoupling the receiving circuit from said transmitting circuit, and a resistance connected with said sending key, said resistance being of such a value that the output current of said transmitting circuit will never fall down to zero.

11. In a duplex telegraph system, more particularly a system of composite duplex telegraphy and telephony, a metallic line circuit adapted to transmit direct current impulses in both directions, a transmitting circuit comprising means for producing alternating current telegraph signals, rectifying means adapted to convert said alternating current signals into direct current signals and to send them into said line circuit, an attenuation network interconnected between said rectifying means and said line circuit, a receiving circuit for receiving direct current telegraph signals from said line circuit, a hybrid coil arrangement for uncoupling said receiving circuit from said transmitting circuit, and a source of direct current connected with the output of said attenuation network for compensating for a steady output current of said rectifying means.

12. In a duplex telegraph system, more particularly a system of composite duplex telegraphy and telephony, a metallic line circuit adapted to transmit direct current impulses in both directions, a two-way repeater device interconnected between two sections of said line circuit, said two-way repeater device consisting of two magnetic one-way amplifiers, two hybrid coil arrangements, each connecting the sending circuit of one of said magnetic amplifiers and the receiving circuit of the other with one of said two line sections and uncoupling said receiving circuit from said sending circuit, a source of direct current for magnetically biasing said magnetic amplifiers, and means for adjusting said biasing

current to such a value as to avoid back-coupling effects within the two-way repeater device.

13. In a duplex telegraph system, more particularly a system of composite duplex telegraphy and telephony, a metallic line circuit adapted to transmit direct current impulses in both directions, a two-way repeater device interconnected between two sections of said line circuit, said two-way repeater device consisting of two magnetic one-way amplifiers, two hybrid coil arrangements, each connecting the sending circuit of one of said magnetic amplifiers and the receiving circuit of the other with one of said two line sections and uncoupling said receiving circuit from said sending circuit, and one-way rectifiers connected in shunt to said magnetic amplifiers, said rectifiers being so biased as to reduce the amplification factor at low amplitudes and thereby avoid back-coupling effects within said two-way repeater device.

14. Telegraphic repeater system, more particularly a wire telegraph system, including telegraph apparatus, a transformer so connected as to protect the telegraph apparatus against disturbing voltages on the line, an alternating current circuit, a key for opening or closing said circuit, rectifier apparatus interposed between said transformer and the line, whereby the alternating current signals produced by operating said key will be converted into direct current signals, which are sent over the line, a choking device located at the receiving end of the line, and means for feeding said device with alternating current, whereby such device will convert the direct current signals into alternating current signals.

15. A telegraph system including a conducting line for the transmission of direct current impulses, a transmitting circuit comprising a source of alternating current and means for transmitting telegraph signals from said source of current, a transformer inductively connected with said conducting line and adapted to protect said transmitting circuit from disturbing voltages on said conducting line, rectifying means interposed between said transformer and said conducting line for converting alternating current telegraph signals transmitted from said transmitting circuit into direct current signals which are to be sent over the line, means for reconverting said direct current signals at the receiving end of the line into alternating current signals, and a receiver responsive to such reconverted signals.

16. A telegraph system including a conducting line for the transmission of direct current impulses, a transmitting circuit comprising a source of alternating current and means for transmitting telegraph signals from said source of current, a transformer inductively connected with said conducting line and adapted to protect said transmitting circuit from disturbing voltages on said conducting line, rectifying means interposed between said transformer and said conducting line for converting alternating current telegraph signals transmitted from said transmitting circuit into direct current signals which are to be sent over the line, means for reconverting said direct current signals at the receiving end of the line into alternating current signals, a receiver responsive to direct current signals, and rectifying means interposed between said reconverting means and said receiver.
